DESIGN FOR A LAMP OR SIMILAR ARTICLE

Francis Paul A. Di Figlia, Brooklyn, N. Y.

Application March 30, 1938, Serial No. 76,182

Term of patent 3½ years

To all whom it may concern:

Be it known that Francis Paul A. Di Figlia, a citizen of the United States and resident of Brooklyn, in the county of Kings and State of New York, has invented a new, original, and ornamental Design for a Lamp or Similar Article, of which the following is a specification, reference being had to the accompanying drawing, forming part thereof, in which,

Fig. 1 is an elevational view of a lamp embodying my design;

Fig. 2 is a top plan view thereof; and

Fig. 3 is a fragmentary perspective view showing the base member partially in section.

I claim:

The ornamental design for a lamp or similar article, substantially as shown.

FRANCIS PAUL A. DI FIGLIA.
